CLAIM

The ornamental design for a combined wood chisel and edge cover therefor, as shown and described.

DESCRIPTION

FIG. 1 is a perspective view of a combined wood chisel and edge cover therefor showing my new design; FIG. 2 is a side elevational view thereof, the opposite side being a mirror image;

FIG. 3 is a top, front and one side perspective view thereof, the edge cover shown removed for clarity of disclosure;

FIG. 4 is a bottom, rear and opposite side perspective view thereof, the edge cover shown removed for clarity of disclosure;

FIG. 5 is a top, front and one side perspective view of the edge cover portion thereof, the chisel being omitted for clarity of disclosure;

FIG. 6 is a bottom, rear and opposite side perspective view of the edge cover portion thereof, the chisel being omitted for clarity of disclosure.
